HYACINTHE MAURICE FAUTEUX Inventor

By

Marion & Marie

Attorneys

UNITED STATES PATENT OFFICE.

HYACINTHE MAURICE FAUTEUX, OF MONTREAL, QUEBEC, CANADA.

SHOE.

1,117,175.

Specification of Letters Patent. Patented Nov. 17, 1914.

Application filed March 28, 1914. Serial No. 827,819.

To all whom it may concern:

Be it known that I, HYACINTHE MAURICE FAUTEUX, a subject of the King of Great Britain, residing at No. 725 Champlain street, Montreal, Province of Quebec, Canada, have invented certain new and useful Improvements in Shoes; and I do hereby declare that the following is a full, clear, and exact description of the invention, such 10 as will enable other skilled in the art to which it appertains to make and use the same.

The invention to be hereinafter described relates to shoes.

15 In order to more clearly disclose the construction, operation, and use of the invention, reference should be had to the accompanying drawings forming part of the present application.

20 Throughout the several figures of the drawings like reference characters designate the same parts.

In the drawings: Figure 1 is a side perspective view of a shoe embodying the invention; and Fig. 2 is a section on line 2—2 of Fig. 1 looking in the direction of the arrows.

25 The main objects of the invention are, to provide a strong, durable, and economical double sole "turned shoe" in which the sole may be made much heavier than at present, and at the same time considerably more flexible than any other double sole shoes, and the means for giving the increased flexibility will be effectually protected from the 35 weather or external wear and tear.

30 This invention is an improvement over the applicant's Canadian Patent No. 144,486 and is intended to remedy certain defects 40 thereof.

In the drawings, 1 designates the upper sole, which is comparatively thin and is provided in its upper face with an outwardly slanting kerf or split 2, which 45 extends around the sole parallel with the edge thereof and a slight distance therefrom. The kerf is extended to such a depth that the main body of sole 1 is connected to the rim portion 1^a by a thin connecting strip of 50 leather. This gives great flexibility to the sole. Because of the thinness of the strip connecting the rim portion 1^a and the body of the sole, there might be a tendency for them to tear apart, at the kerf. To remedy 55 this, a strengthening seam 3 is run vertically through sole 1 from face to face, extends

completely around the edge thereof, parallel with the kerf and a short distance from the lower end thereof. This completely prevents any splitting or tearing of the sole 60 below the lower end of the kerf and, at the same time, greatly strengthens the rim portion and serves to slightly increase the flexibility thereof, as the leather will have a slight flexing along the line of stitching. 65

In securing the sole to the upper the edge of the sole is turned down at an angle from the body, to spread or open the kerf, and a line of stitching 4 is passed diagonally upward from the body of the kerf and through 70 the upper 5 placed thereon. As shown in Fig. 2 the stitching 4 is at right angles to the direction of the kerf and runs upwardly from the bottom thereof only, for a purpose to be later disclosed. After the upper has 75 been secured by the stitches 4 the kerf is closed and cemented, and the upper is turned.

Another important feature of the invention is the interlacing of the threads 4 with 80 the threads 3 of the strengthening seam. As the threads 4 are passed back and forth in the stitching operation they cross the threads 3, and become securely interlaced therewith, each set bracing and strengthening 85 the other, and both co-operating to strengthen the rim of the sole 1.

As will be noted, the sole 1 is made on the extended sole principle, so as to extend well out beyond the upper 5. The heavy sole 6, 90 of the same shape and size as sole 1, is now placed on the under face thereof and secured thereto by a vertical stitching 7, passing through both soles. This lower sole 6 serves to strengthen the sole 1, and also prevents injury to the stitching 3, from bad 95 weather or other external causes. The lower sole also effectually protects the weak point of the upper sole 1, viz., the thin leather strip connecting the body of the sole with the rim portion 1^a. The slight thickness of leather at the bottom of the kerf 2 effectually protects it from any dampness, grit, or the like which might collect between the two soles. These features 100 all combine to produce a very efficient and lasting sole.

By this invention it is possible to produce a shoe having a very heavy double sole, which is very flexible and comfortable, and 110 yet will last for a long time.

It is thought that the construction, opera-

tion, and use of the invention will be clear from the preceding detailed description.

Having thus fully described my invention, what I claim as new and desire to secure by Letters Patent is:

1. A shoe sole provided with a kerf, which leaves the body of the sole connected to its outer part by a thin strip, in combination with an upper, two mutually engaging fastening means extending respectively through said sole from the upper and through said upper and the proximate part of the sole to the bottom of the kerf, a second sole and a line of stitches connecting the two soles together outside of said mutually engaging fastening means.
- 10 2. A shoe-sole provided with an out-

wardly slanting kerf which leaves a thin strip connecting the body of the sole with the outer portion thereof, in combination with an upper, a line of stitches passed upwardly through said thin strip outside of said kerf to said upper, an oblique line of stitches extending outwardly and upwardly from the bottom of said kerf through said upper and interlacing with the line of stitches first mentioned, and a second sole stitched to the first named sole at a point outside of the kerf and stitches aforesaid.

HYACINTHE MAURICE FAUTEAUX.
